UNITED STATES PATENT OFFICE.

BAPTISTE COTE, OF ST. IGNATIUS, MONTANA.

COMBINED ROCK PICKER AND HARROW.

Application filed August 28, 1923. Serial No. 659,784.

To all whom it may concern:

Be it known that I, BAPTISTE COTE, a citizen of the United States, residing at St. Ignatius, in the county of Missoula and State of Montana, have invented certain new and useful Improvements in Combined Rock Pickers and Harrows; and I do hereby declare the following to be a full, clear, and exact description of the invention, such as will enable other skilled in the art to which it appertains to make and use the same.

The object of the present invention is the provision of a machine which is equally well adapted for use both as a harrow and a rock picker and which is simple in construction and effective in operation.

Other objects and advantages will be apparent and suggest themselves as the nature 20 of the invention is understood.

While the drawings illustrate an embodiment of the invention it is to be understood that in adapting the same to meet different conditions and requirements, various 25 changes in the form, proportion and minor details of construction may be resorted to without departing from the nature of the invention.

Referring to the accompanying drawings 30 forming a part of the application:

Figure 1 is a top plan view of a machine embodying the invention;

Figure 2 is a section on the line 2—2 of Figure 1.

Figures 3 and 4 are obverse and reverse side views of the machine;

Figure 5 is a vertical, central longitudinal section, on the line 5—5 of Fig. 1;

Figure 6 is a transverse section on the 40 line 6—6 of Figure 1, and

Figure 7 is a sectional view taken on the line 7—7 of Figure 2.

Corresponding and like parts are referred to in the following description and 45 designated in the several views of the drawings by like reference characters.

The machine embodies a suitable frame including side members 1 and transverse connecting members 2, 3 and 4. This frame 50 is supported by means of caster wheels 5 and drive wheels 6 which are mounted upon axles 7. The middle transverse connecting member 3 is disposed in a higher plane than the front member 2 and the rear member 4 and is connected with the latter by means 55 of spaced ribs 8 which are longitudinally

curved. The space defined by the ribs 8 forms a receptacle for receiving the stones picked up by the machine and this space or receptacle is closed at the rear by means of an end gate 9 which is pivoted to swing upwardly and rearwardly at its lower edge. Catches 10 applied to the rear lower corners of the side members 1 engage the end gate 9 and normally hold it closed. The end 60 gate is provided with a plurality of openings which, together with the spaces between the ribs 8, provide the escape for dirt which is adapted to sift therethrough. The machine may be propelled over the 65 ground in any preferred way and, as shown, a tongue 11 is provided and is connected by hounds 12 with the front ends of the side members 1.

A plurality of gathering and elevating 70 teeth 13 are pivotally connected to the transverse member 2 and their points are adjustable vertically by means of a rod 14 which extends transversely of the machine beneath the teeth 13 and has its ends bent 75 at a right angle and pivoted to the side members 1. A lever 15 mounted upon one of the bent ends of the rod 14, is provided with an arm 16 which engages the rod 14 whereby to adjust the latter vertically and effect vertical adjustment of the forward 80 pointed ends of the teeth 13. A notched bar 17 applied to a side member 1, cooperates with the lever 15 to hold it and the tooth adjusting rod 14 in the required adjusted position. A reel 18 is mounted upon the forward ends of the side members 1 and is adjustable vertically. A lever 19 85 mounted upon a side member 1 cooperates with the reel 18 to effect vertical adjustment thereof, a notched bar 20 cooperating with the lever 19 to hold it and the reel in the required adjusted position. The reel 18 is rotated to cause its teeth to travel upwardly 90 and rearwardly in the spaces formed between the teeth 13, and as a result stones lifted by the teeth 13 are moved upwardly and rearwardly thereover by the teeth of the reel 18. A sprocket wheel 21 fast to an end of the shaft of the reel 18 is connected by means of a sprocket chain 22 with a sprocket wheel 23 loose upon an axle 7 and in this manner the reel is driven by one of the ground wheels 6. A suitable 95 clutch 24 is provided to connect the sprocket wheel 23 with the adjacent drive wheel 6 and this clutch is operable by 100

110

means of a shifter 25, whereby to admit of throwing the reel into or out of action, as required.

An endless elevator 26 is disposed between the teeth 13 and the receptacle for receiving the stones and operates to convey the stones from the teeth 13 to said receptacle. The endless elevator 26 may be of any preferred construction and, as shown, 10 comprises side chains and slats. A shaft 27 is mounted in the side members 1 adjacent the transverse member 3 and is provided at its ends with sprocket wheels 28 which receive the side chains of the elevator 26. A gear wheel 29 fast to an end of the shaft 27 is in mesh with a gear wheel 30 loose on the adjacent axle 7 and adapted to be connected therewith by means of a clutch 31 which is operable by means of a 15 shifter 32, whereby to admit of throwing the elevator into and out of gear, as required. The provision of the gear wheels 29 and 30 causes the upper run of the elevator 26 to travel upwardly and rearwardly, 20 thereby carrying the stones from the teeth 13 into the receptacle at the rear of the machine and closed by means of the end gate 9. A pulley 33 fast on the shaft 27 supports the endless elevator intermediate the 25 sprocket wheels 28. Sprocket wheels 34 mounted upon the inner side of the members 1 adjacent the transverse member 2, support the lower portion of the endless elevator 26, the side chains of which pass 30 around said sprocket wheels 34. A sweep 35 is mounted upon one of the side members 1 and a rein holder 36 is attached to 35 said side member and supports the driving lines in a manner to prevent interference 40 thereof with the reel 18. An arched bar 37 serves to connect the side members 1 and incidentally provides a guard for the reel and elevator.

As the machine is drawn over the field, 45 the teeth pick up stones which are moved thereover by means of the reel and deliv-

ered to the elevator, the latter carrying the stones upwardly and rearwardly and discharging the same into the receptacle from which they are discharged when required by means of the end gate 9. The teeth 13 combined with the teeth of the reel 18 operate in the capacity of a harrow to loosen and lighten the soil, as will be readily understood. 55

What is claimed is:

1. A machine of the character specified including gathering teeth, a reel disposed forwardly of and above the gathering teeth and adapted to coat therewith, and means by which the gathering teeth and reel may be adjusted with respect to each other and to the ground. 60

2. In a machine of the character specified, pivoted gathering teeth, a bar disposed beneath these teeth, means for adjusting the bar to raise or lower the teeth, a reel disposed forwardly of and above the gathering teeth and adapted to coat therewith, and means for raising and lowering said 65 reel with respect to said teeth and the ground. 70

3. A machine of the character specified comprising a frame including side members and a transversely disposed connecting member, gathering teeth pivoted to said transverse member, an adjusting bar disposed beneath said teeth to effect vertical adjustment thereof and having its ends bent at a right angle and pivoted to the side members, a bar operating lever mounted upon one of the bent ends of the bar and provided with an arm engaging the bar, and a notched member cooperating with the lever to secure the teeth in adjusted position. 75 80 85

In testimony whereof I affix my signature in presence of two witnesses.

BAPTISTE COTE.

Witnesses:

A. P. MORSE,
PRUDENT BEAULIEN.
